UNITED STATES PATENT OFFICE.

EDWIN C. LOOMIS, OF CHICAGO, ILLINOIS, ASSIGNOR TO SPENGLER BROTHERS COMPANY, OF CHICAGO, ILLINOIS, A CORPORATION OF ILLINOIS.

KNIFE-GRINDER.

1,078,507.

Specification of Letters Patent. Patented Nov. 11, 1913.

Application filed October 19, 1911. Serial No. 655,619.

To all whom it may concern:

Be it known that I, EDWIN C. LOOMIS, a citizen of the United States, residing at Chicago, in the county of Cook and State of Illinois, have invented certain new and useful Improvements in Knife-Grinders, of which the following is a specification.

This invention relates to means, more specifically intended for domestic use, for grinding knives and other like implements, and one of the principal objects of the invention is to provide an improved, simple and inexpensive device of the class described, which is effective in operation.

Another object of the invention is to provide means to prevent the grinding wheels from being operated in the wrong direction.

A further object of the invention is to provide a novel construction of supporting frame for a device of the class described, whereby the same may be economically stamped out of a piece of metal.

For the attainment of these ends and the accomplishment of other new and useful objects, as will appear, the invention consists in the features of novelty in the construction, combination and arrangement of the several parts generally shown in the accompanying drawings and described in the specification, but more particularly pointed out in the appended claims.

In the drawings Figure 1 is a side elevation of a knife grinder embodying the principles of my invention; Fig. 2 is a plan view of the same; Fig. 3 is a detail view showing a protecting clip; Fig. 4 is an end view of the grinder, parts being omitted; Fig. 5 is a sectional view on the line 5—5 of Fig. 2; Fig. 6 is a perspective view of the frame formed of a single piece of suitable material.

Referring now more particularly to the drawings, the reference numeral 10 designates generally a frame member for the device. This frame 10 is shown more clearly in Fig. 6, in which the side portions 11 are bent downwardly and provided with alined openings 12. One side is also provided with additional openings 13, by means of which it may be secured to any suitable support. Extending upwardly from the main portion of the frame are portions 14 and 15. These portions 14 and 15 are also provided

with alined openings 16 and 17, and the horizontal portion of the frame is provided with rivet holes 18 for guide pins 19. If desired, spacing bars 20 may be provided, which are secured to the lower ends of the frame to provide additional rigidity.

Mounted in the alined openings 12 is an operating shaft 21, provided at one end with a threaded stem 22, and a hand lever 23 is mounted upon the stem 22. No securing means is provided for retaining the lever 23 upon the stem 22, so that the operating shaft 21 may be rotated in one direction only. When an attempt is made to rotate the shaft in the reverse direction, the hand lever 23 is turned on the stem 22 without producing any rotation of the shaft. Mounted upon the operating shaft are gears 24, which are provided with worm teeth and are disposed upon the shaft so that the teeth are inclined in opposite directions.

Mounted in the alined openings 16 and 17 are shafts 25. These shafts are preferably provided with a conical opening 26 at each side of the shaft, into which there extends a conical tip 27 of a threaded screw pin 28. These pins 28 are preferably threaded in the openings 16 and 17, and are each provided with a lock nut 29 to secure the screw pin in position. Each shaft is provided with a ring secured to it, or a shoulder 30 formed integral therewith adjacent the one end, and upon this end a plurality of grinding wheels 31 are disposed, suitably spaced apart by blocks 32 and retained in position upon the shaft by means of a lock nut 33. The shafts 25 are spaced apart, the distance apart being less than the diameter of one of the grinding wheels 31, so that when the grinding wheels are in position upon the shafts the contiguous edges of the wheels upon one shaft extend beyond the edges of the wheels mounted upon the other shaft. This necessitates the spacing apart of the grinding wheels, so that the edge of one wheel projects between the edges of two other wheels mounted upon the other shaft.

To rotate the shafts 25, worm gears 34 are mounted upon the shafts, preferably adjacent the end opposite to that at which the grinding wheels are located, and meshing with the gears 24, which are mounted upon the shaft 21. It will be evident that the

- 2
- direction of rotation of one of the shafts will be opposite to that of the other shaft, and that it will be impossible to rotate the grinding wheels in the reverse or wrong direction. In grinding the adjacent edges of the wheels 31 will be moved upwardly. If they were moved in the other direction there will be a tendency of the article ground to bind between the wheels, and this would of course be objectionable.
- 5 10 The guide pins 19 which are secured to the frame preferably extend upwardly at the edge of two oppositely rotating wheels, so that the blade to be sharpened when 15 pressed downwardly upon the grinding wheels is retained in upright position by means of these guides.
- To prevent the grindings from the wheels 20 falling upon the gears 24, a shield 35 is provided, which is secured to the frame 10 adjacent its horizontal portion and extends upwardly over the gears 24 below the shafts 25. This shield prevents the grindings from entering the teeth of the gears 24 and thereby causing them to wear 25 uniformly.
- The upwardly extending portion 15 of the frame is preferably formed with a grooved portion 36, in order to give it additional 30 rigidity, and to the upper end of this portion 15 there is secured a shield 37, which extends over the gears 24, mounted upon the shafts 25, and in close proximity to the grinding wheels mounted upon the shafts.
- 35 The object of this shield is to protect the operator from the gears 34, and to prevent the grindings from coming in contact with the said wheels. The shield 37 also provides a supporting surface for an L shaped clip 40. 40 These clips 38 and 40 are preferably composed of a softer material than the material of which the frame is constructed, so that if the sharpened edge of a knife or other article comes in contact with the clip the edge 45 will not be injured thereby. The clips are in alinement with the guide way formed by the guides 19.
- What I claim is:
1. In a device of the class described, the combination with a frame member formed of a single sheet of material with upwardly extending perforated portions, a pair of parallel shafts mounted at both ends of the shafts in said portions, grinding wheels adjustably mounted on the shafts, a transverse shaft disposed below the other shafts and mounted in the frame, intermeshing gears mounted upon the shafts, and means to rotate each of the shafts in a single direction.
  - 65 2. In a device of the class described, a frame element made of a single sheet of material formed with depending side portions having alined openings, and with upwardly extending portions having a plurality of alined openings.
  3. In a device of the class described, a frame element made of a single sheet of material formed with depending side portions having alined openings, and with upwardly extending portions disposed substantially at right angles to the depending sides, one of the upwardly extending portions being rounded and formed with a groove to give additional rigidity.
  - 70 4. In a knife grinder, the combination of a frame element formed from a single piece of sheet material having opposite depending side portions and upwardly extending portions disposed at right angles to the depending portions, said portions being provided with alined openings, parallel shafts mounted in some of said openings, and an operating shaft disposed in other openings at right angles thereto, grinding wheels adjustably positioned on the parallel shafts, 80 worm gear wheels mounted upon the parallel shafts, other gears mounted upon the transverse shaft and meshing with the first named gears, and a crank threaded on the transverse shaft to rotate it operatively only 85 in one direction.
  5. In a knife grinder, the combination of a frame element formed from a single piece of resilient sheet material having depending side portions and upwardly extending portions disposed at right angles, said portions being provided with alined openings, parallel shafts having bearing openings in the ends, a screw pin having a bearing tip to fit the said opening and threaded in the alined 100 openings for the shaft, lock nuts to retain the screw pins in position, grinding wheels positioned on the shafts, and means positioned in the frame to rotate the said shafts.
  - 105 6. In a device of the class described, the combination with a frame element having upwardly extending sides provided with alined openings, parallel shafts mounted in said openings, grinding wheels adjustably mounted upon the shafts, gears secured to the shafts, means to rotate the shafts, and a shield secured to the frame element on one of the sides thereof and extending over the 110 said gears on the shafts.
  7. In a device of the class described, the combination of a frame element having upwardly extending sides formed with alined openings, parallel shafts mounted in said openings, grinding wheels adjustably mounted upon the shafts, gears secured to the shafts, means to rotate the shafts, a shield secured to one extending end of the frame element and disposed over the gears, and means to protect the blade to be sharpened, 115 comprising a soft metal clip secured over 120 125 130

the shield at one end of the frame element, and a soft metal clip positioned over the other upwardly extending side, the said clips being in the line with the grinding position:

In testimony whereof I have signed my name to this specification, in the presence

of two subscribing witnesses, on this 17th day of October A. D. 1911.
